HOLDER FOR ICE BUCKET OR SIMILAR ARTICLE

Lud H. Kimbrough, Jr., Richmond, Va., assignor to Ideal Fishing Float Company, Inc., Richmond, Va., a corporation of Virginia

Filed Apr. 12, 1961, Ser. No. 64,753

Term of patent 3½ years

(Cl. D58—26)

The holder is circular in cross-section and the bottom not shown is open.

The rear not shown is the same as the front shown.

I claim:

The ornamental design for a holder for ice bucket or similar article, as shown and described.
